FIG. 4

FIG. 1

FIG. 2

FIG. 3

INVENTOR
Char Ruiz

UNITED STATES PATENT OFFICE.

CHARLES RUIZ, OF BELLEVILLE, NEW JERSEY.

VALVE-GRINDING DEVICE.

Application filed June 13, 1921. Serial No. 477,318.

To all whom it may concern:

Be it known that I, CHARLES RUIZ, a subject of the King of Spain, and a resident of Belleville, in the county of Essex and State 5 of New Jersey, have invented certain new and useful Improvements in Valve-Grinding Devices, of which the following is a full, clear, concise, and exact description, reference being had to the accompanying drawings, forming a part of this specification.

This invention relates to valve grinding tools of the oscillating progressive type, designed to be manually operated by imparting an oscillating movement to the valve being 15 ground and the arcs of rotation being of different circular length in each reversing stroke so as to impart to the valve a rotating as well as an oscillating motion.

To this end, the invention consists of a 20 novel construction and arrangement of parts hereafter described in detail and pointed out in the appended claims, reference being had to the accompanying drawings in which:

Fig. 1—is a front view of the tool with 25 half of the case removed.

Fig. 2—is a vertical cross sectional view through line C—D.

Fig. 3—is a fragmentary cross sectional view through the line A—B.

Fig. 4—is a view of the sleeve.

Similar characters of reference refer to 30 similar parts throughout the several views.

As illustrated in Figs. 1 and 2, the valve grinder comprises a special body integrally 35 cast with a handle, and vertically split in two halves for the purpose of assembling the enclosed parts. Said casing is designated by numerals 1 and 2.

Numeral 3 indicates the shaft on which is 40 mounted a suitable tool 4 to fit the valve to be ground. In this particular design the tool is held by means of a cotter pin 18.

Sleeve 5 is mounted on shaft 3 and is free 45 to rotate on it. Two bevel gears 6 and 7 are mounted on said sleeve 5 and form an integral part of it. Pin 8 is driven into shaft 3 and its ends project through hole 9 in sleeve 5. Spring 10 is for the purpose of holding pin 8 against one side of hole 9 in sleeve 5.

Ball 11 is for the purpose of taking the 50 end thrust when the tool is in operation. Numeral 12 indicates a mutilated bevel gear, said gear being mounted on shaft 13 and

forming an integral part of it. Crank 14 and crank handle 15 are used as means for 55 operating the tool.

In this particular design, the case is made in two halves, held together by means of rivets indicated by numeral 16 and the body of the tool is made spherical and integrally 60 cast with holder 17.

In operation, upon turning crank handle 15 mutilated gear 12 is made to rotate with it and thus the teeth in said gear alternatively engage with upper and lower bevel 65 gears 6 and 7 which as it is apparent will in turn oscillate shaft 3 which is driven by means of pin 8.

The advancing is obtained as follows: In 70 operation the valve being ground will create friction on the shaft and when the teeth in gear 12 enter into engagement with gear 6 will move pin 8 to position shown in dotted lines in Fig. 3, the angular motion of said pin in the hole being equal to one or more 75 teeth in gears 6 and 7. When the last tooth in gear 12 disengages gear 6 the pressure on spring 10 is released and said spring will bring sleeve back to original position in relation to pin 8 and shaft 3. 80

When gear 12 engages with gear 7 the shaft is driven by means of pin 8, but spring 10 does not operate and of course, the shaft is driven forward an amount equal to the 85 number of teeth in mutilated gear 12 while on the engagement with gear 6, a motion equal to one or more teeth was lost due to clearance in the hole 9 and the action of spring 10.

It will be noticed from the foregoing that 90 in order to advance the position of the tool bit in each oscillation, a pressure greater than the spring must be applied on the shaft, although the shaft will oscillate under any condition. 95

Having thus described my invention what I claim as new is as follows:

In a valve grinder of the oscillating progressive type, the combination of a case, a driven shaft journaled therein and having 100 means for engaging a valve to be ground, and a laterally projecting pin, a sleeve loose on the shaft having a hole larger than and receiving the pin and two bevel gears of the same size, a spring fast to the sleeve and 105 bearing against one side of the pin, a mu-

tilated bevel gear mounted in the case to mesh with said first mentioned gears laterally, and a hand crank for operating said mutilated gear, whereby the shaft is oscillated to a greater extent in one direction than in the other.

In testimony whereof I have hereunto set

my hand in presence of two subscribing witnesses.

CHAS. RUIZ.
